UNITED STATES PATENT OFFICE.

GEORGE CALDER, JR., OF LANCASTER, PENNSYLVANIA, ASSIGNOR TO MARY H. CALDER, OF SAME PLACE.

MATRIX-MAKING MACHINE.

SPECIFICATION forming part of Letters Patent No. 445,040, dated January 20, 1891.

Application filed April 14, 1890. Serial No. 347,854. (No model.)

To all whom it may concern:

Be it known that I, GEORGE CALDER, Jr., a citizen of the United States, residing at Lancaster, in the county of Lancaster and State of Pennsylvania, have invented certain new and useful Improvements in Matrix-Making Machines; and I do hereby declare the following to be a full, clear, and exact description of the invention, such as will enable others skilled in the art to which it appertains to make and use the same.

The object of the invention is to provide an efficient and compact machine for impressing matrices.

The present improvements relate to a machine described in my application filed January 31, 1890, and serially numbered 338,744. In said application were described the main features of the machine herein set forth; and the present invention consists in the improvements hereinafter described, and particularly pointed out in the claims.

In the accompanying drawings, Figure 1 is a vertical section on line X X of Fig. 2. Fig. 2 is a plan partly in section. Fig. 3 is a vertical section on line y y of Fig. 1. Fig. 4 is a partial vertical section on line z z of Fig. 1. Fig. 5 is a plan of gears and rack for moving the matrix-bed, the alternative position of gears and their supporting-frame being indicated by dotted lines; Fig. 6, a section on line t t of Fig. 5. Fig. 7 is an elevation of cock-operating mechanism, the cocks being shown in section; and Fig. 8 is a side view of the same, the cocks being omitted. Fig. 9 is a vertical section through the type-carrier gear-wheel. Fig. 10 is a transverse section of the type-carrier. Fig. 11 is an elevation of the type carrier gear-wheel. Fig. 12 is an edge view of driving-gears shown in Figs. 5 and 6, the pawl, spring, stop, and rack-bar being omitted.

The frame of the machine consists of the floors or tables a, b, c, and d, tied together by rods 74 and kept in proper position by the tubular stays 74', which surround the rods and abut against the floors. Above the machine is suitably supported a cylinder 10, in which works the piston of a type-hammer.

Below the hammer and above table a is arranged a type-carrier 9, curved in cross-

section and having fixed thereto a shaft 75. This shaft has a free endwise motion through the hub 25' of a gear-wheel 25, but is keyed thereto at 91, so that they revolve together. The gear-wheel 25 has a bearing on post 32. 55 At the opposite end of the type-carrier it is fixed to the rod of a piston working in cylinder 8, and it is moved back and forth by pressure on the piston. This movement carries the shaft 75 to and fro over series of stops. 31 denotes 60 one or more of such series, and 3 an individual stop. The object of the gear-wheel is to turn the type-carrier until the desired series of type, of which there may be several arranged lengthwise of the carrier, is under 65 the hammer, and the purpose of the stops is to arrest the longitudinal movement of the type-carrier at the time when the desired type of any series is under the hammer.

Below the hammer and type-carrier is the 70 matrix bed or cylinder 14, rigidly connected to a shaft 28, which has bearings in stand 20 and in central apertures in a ratchet-wheel 27 and weight-pulley 33, said pulley and ratchet having bearings upon posts 34 and 75 98. The shaft is so keyed to the pulley and ratchet-wheel as to revolve with them. It, however, moves freely through them in endwise direction. On one end of shaft 28 is a piston working in cylinder 18, which cylinder 80 receives compressed fluid through pipe 30 and stand 20, the piston being thereby normally forced to the outer end of the cylinder. The purpose of this arrangement is to return the matrix-bed after it has been moved in the 85 opposite direction to impress a line thereon, as will be explained. The purpose of the ratchet 27 is to move the matrix-bed circumferentially the distance of one or more lines. This ratchet has a spline or key connection 90 with the shaft similar to that indicated in Fig. 11 to permit free endwise motion of the shaft through the ratchet, while compelling them to rotate together. The object of the pulley and weight is to keep the spline or key 95 in close and constant contact with its seat in the shaft to insure accuracy and uniformity of alignment of the matrix-bed.

The above-described devices are operated by means which will be now described. 100

81 and 82 are pipes communicating with a reservoir of compressed air or with any source of fluid-pressure. These pipes also communicate with cylinder 8, one on each side of its 5 piston, whereby it and the connected type-carrier can be moved in either direction.

15 15 are two-way cocks arranged one in each of said pipes and adapted to permit the compressed fluid to pass to or from the cylinder, according as they are turned, substantially as indicated in Fig. 7. 16 16 are similarly-arranged cocks by which the compressed fluid can be passed through suitable pipes to the hammer-cylinder 10 on either side of its 15 piston and discharged into the open air from the other side, as also indicated in Fig. 7, the several pipes and their connections being shown in Figs. 1 and 2. The cocks 15 and 16 are operated by a rod 83, pivotally connected 20 with an arm of a lever 6, which is moved about a supporting-rod 6'. Parallel to the power-arm of lever 6 is a bar 6², which at its outer end is connected by a bar or platform 6³ (see dotted lines in Figs. 2 and 3) to the outer end of 25 lever 6 and extends beyond the same and under the key-rods 11. These rods extend to the top of the machine and are provided with suitable heads or finger-pieces and correspond each to a distinct letter or character.

30 In the present instance the six keys at the right of the key-board are intended for operating mechanism to move the matrix-bed without impressing the matrix to provide for a spacing and blanks. Under these the trans- 35 verse bar 6³ does not extend, and they will not therefore operate the valves 15 and 16. If any key-rod over bar 6³ is depressed, it moves lever 6 and raises rod 83. This rod is connected to arms 15' and 16' of the plugs of the 40 several cocks 15 and 16 by pivoted rods, and the cocks are arranged in such manner that the cock in pipe 81 will be opened to permit compressed air or other fluid to enter cylinder 8 to move the type-carrier under the hammer 45 in time to receive the impact of the hammer, which is operated nearly simultaneously by the opening of the cock 16, that admits air to cylinder 10 above the hammer-piston, the cock in pipe 82 and the other cock 16 being 50 at the same time opened to the air to waste or exhaust from in front of the respective pistons. The return or falling movement of bar 83 reverses the several cocks and admits compressed air to the other side of the pistons, the air which was just before admitted 55 to the cylinders being thereupon exhausted.

The type-carrier 9 is provided with several series of types or characters arranged longitudinally therein. The mechanism for arresting the carrier at the proper time to put a particular type under the hammer includes a stop 3, of which there are several series, corresponding to the type series, and means for raising said stop into the path of the bar 75. 65 This is effected by a spring-lever 2, which has its fulcrum on a fixed rod 77, there being a lever for each stop. One end of each lever 2

is engaged in a slot in a key-rod 1, and the other end extends under the foot of a vertically-movable stop 3. When a rod 1 is depressed, it operates its lever 2 to raise a corresponding stop, the spring 2 being at the same time put under sufficient tension to return the key. Thus the striking of the key-rod corresponding to a letter or character 70 75 raises the proper stop to arrest the lengthwise movement of the type-carrier when the desired type is under the hammer.

The type-carrier is moved circumferentially to bring any particular series under the hammer by means of a rack-bar 24, which gears with the wheel 25, which is keyed to shaft 75. This bar 24 rests upon table a, and is locked in position by a spring-pin 80, which passes therethrough and through a slot in the table, 80 85 and has at its foot lateral projections 99, which engage suitable depressions in the under side of the table formed on one or both sides of the slot. These depressions are arranged to correspond with suitable adjustment of the several series of type and of intermediate mechanism, and the type series corresponding to each may be noted on the upper side of the table adjacent to the slot. The spring 100 normally holds the pin up 95 with its foot engaged in a depression.

The matrix-bed is moved by means of the cams 4 on rods 1, which when the rod is depressed push plates 5 or 7 (see Fig. 2) to suitably move ratchet-wheels 11 or 17 by the intermediate mechanism.

37 is an actuating-pawl (see Figs. 1 and 2) carried by an arm 38, rigidly attached to a hub or cylinder 64, turning loosely on shaft 63, to which latter the ratchet-wheels 11 and 17 are fixed. Sliding plate 5 has pivoted connections with the arms 38, and when it is pushed forward by a cam 4 it partially rotates the hub 64 and arms 38 and forces forward the pawl and partially turns ratchet-wheel 11 and shaft 63 and bevel-gears 40 on the inner end of said shaft and also the vertical shaft 41. This shaft 41 has its lower end stepped in a bracket secured to floor c, (see Fig. 1,) and has affixed to it one of the 115 bevel-gears 40. Gear-wheels 42 and 43 are rigidly fixed to said shaft 41 and turn with it.

44 and 45 are intermediate gears, the teeth of the former meshing with those of 43 and the teeth of 45 with those of 42.

60 is the handle of a crank rigidly attached to a shaft 60', carrying at its lower end a frame 59, fixed thereto, in which the gear-wheels 44 and 45 are journaled, and by said crank and shaft either of these wheels can be 125 thrown into gear with a wheel 46, the wheel-supporting frame 59 being thereby suitably turned for the purpose and the desired wheel held in such engagement by means of the handle 60, which has a locking-pin that passes 130 through the crank and can be engaged with suitable depressions in the table b. The wheel 46 can therefore be driven either by gear 42 or 43, and therefore at a different speed.

The practical object of the above-described change of gears is to vary the speed to provide for moving the matrix-cylinder through different units of distance at will, according 5 to the requirements of type of different fonts. As represented in the drawings, it is calculated that where the ratchet-wheel 11 is advanced the distance represented by one tooth of the matrix-cylinder by means of the intermediate mechanism, including gears 45 and 46, will be moved lengthwise one thirty-second of an inch, whereas if wheel 44 were substituted for 45 by suitably shifting frame 59 (see Fig. 6 and dotted lines Fig. 5) the movement 15 of the cylinder would be one forty-eighth of an inch.

As indicated in Figs. 5, 6, and 7, gear 45 is engaged with and drives gear 46, being itself driven by gear 43. By a partial revolution 20 of shaft 60' the frame 59 will be turned and carry gear 45 out of and gear 44 into engagement with wheel 46, gear 44 being driven by gear 43. The speed of wheel 46, and consequently of wheel 12 and bar 13, will then 25 correspond to the size of this driving gear or pinion, and this adjustment provides for using fonts of type of different size.

Wheel 46 is connected by a pawl, to be hereinafter described, to a wheel 12, which 30 gears with a rack-bar 13 and moves it to the left under the operation above described. This rack, which rests upon table *b*, is provided with flanges or projections 32, that embrace the ends of the matrix-bed 14, so that it is 35 moved longitudinally with the bar, but may rotate independently of it. The described movement of bar 13 moves the matrix-cylinder and its shaft against the pressure in cylinder 18, before described. The extent of this 40 movement is predetermined by the width or face length of the particular cam 4 on the operating key-rod that moves it, and this length is appropriate to the particular letter represented by the rod. To still further 45 modify the extent of said movement to adapt the mechanism for larger or smaller fonts of type, the movement of the driving-pawl 37 is modified by the following devices:

50 56 is a swinging stop abutting against said pawl. It is provided with a curved arm 57, that rests on pawl-arm 38, to which is pivoted the pawl 37 and against which the stop also bears. The stop 56 is pivoted to a bell-crank 55 on a shaft 58, journaled in hanging brackets 55 attached to floor *b*.

The ratchet-wheels 11, pawls, stops, arms, and bell-cranks are in duplicate, as indicated in Fig. 1.

60 65 is a weighted arm rigidly attached to an arm 38, which latter is loosely mounted on shaft 63 by means of the hub or cylinder 64. The weight 65 keeps the arm 38 in contact with the stop 56, and the latter is moved when desired by the bell-crank 55, which being 65 turned on its supporting-shaft 58 carries the stop to the right or left, as desired. The position of the bell-crank is determined by means

of the vertical bar 54, which in turn is held at different elevations against the transmitted force of weight 65, tending to raise it by the 70 rack-bar 24, which has upon its under side various depressions to receive said bar. The pawl-arm 38 and the plate 5 are moved to the left toward rod 1 by the constant action of the weight 65 as far as bar 24, rod 54, and 75 stop 56 will permit, and this distance is regulable by means of the shoulders or cut-away portions in the under side of bar 24. If, for example, a part of the bar that will depress rod 54 below any given position is brought 80 over it, the slide 5 will be moved away from rod 1, the bell-crank slightly turned on its pivot by the stop, and the arm 38 moved about shaft 63. Consequently the slide 5 will be farther from rod 1 and cam 4, and the latter 85 will descend a short distance before the cam will engage plate 5 and begin to move the same. Said plate will therefore be moved a less distance than otherwise, as also will be the pawl and ratchet-wheel, and consequently the 90 corresponding movement of the matrix-bed will be less, and by this means the described parts can be adjusted to move the bed as required by fonts of different-sized type, the relative variations for different thicknesses 95 of individual type, dependent on the differences in the cams 4, remaining practically the same.

To provide for the return of the matrix-bed after the completion of a line without reversing all the gears, the wheel 12 is temporarily disconnected from wheel 46.

49 is a pawl fixed on a pivot or axis which is journaled in the wheel 12, and which pivot has fixed to it upon the upper or opposite 105 side of 12 an arm 48, the pawl 49 being arranged to engage an internal ratchet 51 in wheel 46. The arm 48 is pressed by a spring 47, which holds the pawl in engagement with rack 51 until it is tripped by the arm 48 striking a stop 50, whereupon the pawl is thrown out of engagement and wheel 12 is free to be moved by the rack 13, which under such circumstances will be carried to the right by the air-pressure in cylinder 18. The stop or trip 110 50 is made adjustable by the crank and pin 61 to adapt the movement of the parts to forming lines of different lengths. The wheel 12, disengaged from 46, is turned back by the return of the matrix-bed and rack 13 until its 115 pawl 49 is again engaged with rack 51 in wheel 46 by the pawl-arm 48 coming in contact with a pin or stop 53, suitably supported in the frame. It will be understood that the pawl 49 and its tripping-arm 48 are on opposite sides of gear 12. A part of the latter is broken out in Fig. 5 to show the relative position of the pawl and its arm, both being secured to the pin 48', which is loosely supported in the gear-wheel 12.

The matrix-bed is moved circumferentially after the completion of a line of impressions thereon by the means now to be described.

27 is a ratchet-wheel keyed or splined to

shaft 28, to which the matrix-bed is rigidly affixed.

73 is a bell-crank lever, to one arm of which a driving-pawl 71 is pivoted, as shown in Fig.

5 4. On the end of rack 13 is formed a cam or incline 13', which is drawn past the pendent arm of the bell-crank lever and in contact with it when said bar 13 is returned upon the completion of a line. The cam at such 10 time has the effect to move the pendent arm 73 of the lever, thereby raising the outer end of the other arm 72 and forcing forward pawl 71 and moving ratchet-wheel 27 and consequently the matrix-bed, a distance determined by the adjustment of stop 69. The 15 horizontal arm of the bell-crank is held up by said stop, and the position of arm 73 with reference to the vertical line and with reference to bar 13 and cam 13' is therefore dependent upon this stop. If it be lowered, 20 arm 72 follows it by gravity, and arm 73 is moved to the left or toward bar 13, and will consequently be more affected by the described action of cam 13'. On the other hand, 25 if the stop be raised and arm 72 and the pawl be correspondingly elevated, arm 73 will be moved away from rack 13, and its cam will have less effect to move it and pawl and ratchet and matrix-bed. Stop 69 is adjusted 30 by moving crank 66 and the cam 67 about the vertically-movable rod 68, whereby it is raised by a pin 86 riding up the face of the cam, or is lowered by gravity when the pin rides down the same. A pin in arm 66 and 35 a series of holes in the table with a suitably arranged dial thereunder enable this adjustment to be intelligently and securely made. 70 is a retaining-pawl.

The construction of the type carrier, clearly 40 illustrated in Figs. 1 and 10, is substantially that described in my former application above referred to, the type being held in its seat by a spring. The stop-bar 75 was also shown in said application; but in the present instance 45 I have provided it with a cap or bumper 90, which may be secured to the bar by a screw 94 or otherwise. It contains an elastic cushion 95. Said cap 90 has a plain face on its under side, which moves over the bench or 50 group of stops. (See Fig. 1.)

By the above-described mechanism the type-carrier can be moved with certainty and ease and stopped without rebound or jar. The sliding bar 7, it should be understood, is 55 operated by the keys adjacent to it, six in number in the present instance. This slide is connected to an arm 7', that carries a driving-pawl which moves forward ratchet 17 and shaft 63 with the effect to move the gears, 60 rack, and matrix-bed, as already described. The rods operating slide 7 have, however, no connection with lever 6 nor with the valve mechanism, so that they move the matrix-bed without causing it to be impressed.

65 In my application above named were described and claimed a revoluble type-carrier having an axis or shaft keyed to a rack in

such manner as to provide for rotating the carrier by means of the gear and for an independent longitudinal movement of said carrier; also, a circumferentially-grooved matrix-cylinder, the groove being engaged by a rack-bar, and mechanism for moving the bar, a piston-cylinder, and piston on the matrix-cylinder shaft; also, a combination of the latter devices with the air-cocks of the piston-cylinder, and also a combination of the same with devices for releasing said rack from its driving gear-wheel to permit its return to its initial position without a reversal of the driving mechanism, and such devices and combination are not herein claimed.

Having thus described my invention, what I desire to secure by Letters Patent is—

1. In a matrix-impressing machine, the type-carrier provided with a shaft having on its free end an elastic cushion or bumper, in combination with a stop and with means for moving the carrier lengthwise and for moving the stop in the path of the shaft, substantially as set forth.

2. In a matrix-impressing machine, a matrix-bed fixed to a longitudinally-movable shaft having a piston on its end, a cylinder in which said piston moves, an inlet for compressed air, devices for moving the matrix-bed and the piston against the air-pressure, and a tripping device whereby when the devices for moving the bed are tripped the bed is returned to its initial position by the air-pressure on the piston, substantially as set forth.

3. In a matrix-impressing machine, the matrix bed fixed to a shaft, a ratchet-wheel, and a pulley, the wheels and pulley being keyed to the shaft, a weight on the pulley to keep the key always in contact with its seat on the same side thereof, and mechanism for moving the bed lengthwise and for producing lines in the matrix, substantially as set forth.

4. In a matrix-impressing machine, the matrix-bed fixed on a shaft, the rack provided with projections embracing the bed and with a cam or incline, devices for moving the rack, a ratchet-wheel keyed to the shaft, a pawl for driving the wheel, having an arm arranged in the path of the cam-face on the rack, and devices for moving the cam against the arm, whereby the matrix-bed is moved lengthwise and thereby partially rotated, substantially as set forth.

5. In a matrix-impressing machine, the matrix-bed fixed on a shaft, the rack provided with projections embracing the bed and with a cam or incline, devices for moving the rack, a ratchet-wheel keyed to the shaft, a pawl for driving the wheel, having an arm arranged in the path of the cam-face on the rack, and devices for moving the cam against the arm, whereby the matrix-bed is moved lengthwise and thereby partially rotated, and an adjustable stop to vary the throw of the pawl-arm and the rotation of the bed, substantially as set forth.

6. In a matrix-impressing machine, a key-
rod provided with a cam, a sliding plate mov-
able by the cam, a ratchet-wheel to drive the
matrix-bed-moving mechanism, a weighted
5 pawl-arm loose on the shaft of the ratchet-
wheel and connected to the sliding plate, a
pawl pivoted to said arm, a swing-stop, the
weight of the pawl-arm being arranged to
keep the stop against the arm, and devices
10 for adjusting the stop-arm and slide to vary
the effect of the cam on the slide, substantially
as set forth.
7. In a matrix - impressing machine, the
swinging stop pivoted to the bell-crank, the
15 bell-crank, the rod pivoted thereto, and the
movable bar having depressions of varying
depths, in combination with the driving-pawl,
ratchet, intermediate gears, and matrix-bed,
substantially as set forth.
- 20 8. In a matrix - impressing machine, the
movable rack-bar having depressions of vary-
ing depths, the gear-wheel keyed to the shaft
of the type-carrier, the vertical rod, bell-
crank, stop, pawl, pawl-arm, sliding plate, and
25 key-rod, all in combination, whereby the rack

that turns the type-carrier also adjusts the
length of movement of the rack that trans-
mits motion to the matrix-bed, substantially
as set forth.

9. In a matrix-impressing machine, a key- 30
board, a hammer, a type-carrier provided with
series of type, a matrix-bed, mechanism for
moving the carrier and mechanism for mov-
ing the bed, and a bar that moves the carrier
and also adjusts the extent of the movement 35
of the bed under the influence of the rod, sub-
stantially as set forth.

10. In a matrix - impressing machine, the
combination of the key-rods and intermediate
mechanism with gears made interchangeable 40
and with the matrix-cylinder, whereby the ex-
tent of the movement in the direction of the
line of the latter may be varied, substantially
as set forth.

In testimony whereof I affix my signature in 45
presence of two witnesses.
